METHOD AND APPARATUS FOR CONCENTRATING ORES

Franklin F. Grant, San Diego, Calif.

Application November 12, 1935, Serial No. 49,361

6 Claims. (Cl. 209—183)

My invention relates to apparatus for concentrating ores, and its objects are to effect a more complete separation of the metals from the gangue, to produce a closer association of the metals in the ore with mercury for the purpose of producing an amalgam, to utilize the gravity of the ore pulp in bringing about such separation, and to render more simple, efficient, cheap, and expeditious the extraction of the metals from the ore or other material in which the same may be found.

In the ordinary operation of separating metals from a mixture of water and the gangue through gravity, such as panning in placer mining, the materials sink to the bottom and the earthen substance is carried off with the water. This method of separation while effective requires a maximum of human effort, takes much time and is tedious. Various mechanical means have been employed for the utilization of these principles, but so far as I am aware no person has ever produced and maintained within a confined space a layer of mercury of substantially uniform thickness and through the sole use of gravity has caused the ore pulp to flow tangentially within such space and to impart a vortex movement of the mixture for the purpose of effecting a closer association of the materials and the formation of a better amalgam than has been heretofore accomplished, or has employed other novel features of my invention hereinafter more particularly set forth.

In utilizing my invention, I prefer to employ a hopper capable of supporting a vertical column of fluid pulp containing ore, which hopper is reduced in diameter at the bottom, and is provided with narrow openings or slots disposed at an angle to the wall of such hopper for the purpose of causing a tangential outpouring of the fluid pulp therein contained. Adjacent to and surrounding these tangential openings, I preferably locate a funnel shaped receptacle filled with mercury to a level sufficient to cover such openings, and I also provide means for carrying off the overflow of such material as may pass through the mercury.

Attention is directed to the accompanying drawing in which similar numerals of designation refer to similar parts throughout the several views.

Figure 1 is a vertical section of my improved apparatus, the arrows denoting the direction of the flow of the pulp fluid;

Fig. 2 is a horizontal section of the apparatus illustrated in Fig. 1, on line 2—2 thereof, look-

ing in the direction of the arrows and showing the lower part of the hopper and adjacent parts;

Fig. 3 is a horizontal section of the mouth of the hopper on line 3—3 of Fig. 1, looking in the direction of the arrow and showing the location of the central discharge opening and the tangential spouts.

Referring to the drawing, the hopper 5, preferably constructed of metal or other similar material, is in the form of a long cylinder vertically disposed, and is provided at the base thereof with a cone shaped bottom 12, through which extends the central opening 13, and the openings 14. As will be observed, the openings 14 are provided with the lips 15, forming spouts tangentially disposed. Surrounding the major portion of the hopper 5 is the tank 4, also preferably of metal or other suitable material, and having at the top thereof an annular rim, contacting with a cover 7, affixed to the upper part of the hopper 5 and serving to support the same. Spacers 16, of which four (4) are here shown and which are secured to the wall of the hopper 5, serve to hold such wall in proper spaced relation to the wall of the tank 4. At the lower part of the tank 4 is located funnel 8, having an outlet 9, normally closed by the valve 10. At some convenient part of the tank 4, preferably the lower portion thereof, is located outlet 1, provided with a stop cock or faucet.

As will be observed, the wall of the funnel 8 is parallel to and near the wall of the cone shaped bottom 12, leaving a narrow passageway therebetween. Wherever in this specification or the appended claims, I refer to funnel shaped bottoms, I desire to be understood as meaning a bottom in the shape of a hollow cone or pyramid which is slightly truncated, and the wall of which is at a substantial angle with the axis thereof.

In the upper part of the tank is located spout 6, providing the normal egress to waste fluids within the tank. Although normally, I prefer to operate my preferred form of apparatus in batteries of two or more units, supported in any manner well known in the art, I find it desirable in a single form of apparatus, to supply the tank with legs 11, in order to hold the tank in operative position.

To operate my form of apparatus here shown, the hopper 5 and tank 4 are first preferably separated. Thereupon the funnel 8 is filled with a quantity of mercury 11, and the hopper 5 is thereafter installed in the position shown in the drawing. If desired, however, without disassociating

the hopper 5 and the tank 4, the mercury may be introduced through the opening at the top of the hopper 5 or through the outlet 6 into the tank 4, in which case the mercury will flow 5 downwardly into the funnel 8. The material containing the ore to be treated is pulverized, if necessary, and is mixed with water to form a fluid pulp, which is preferably one-half ($\frac{1}{2}$) water by volume, but which may be any liquid 10 consistency sufficient for the purpose. Where the metals are free as in the case of gold found in earth, as in placer mining, (that is free gold), it will not be necessary to pulverize the ore, but otherwise it will be necessary to crush the material in order to free the metals. This fluid pulp 15 designated in the drawing by the numeral 18 is then introduced into the hopper 5, which is filled and preferably kept filled to a level near the top of the hopper 5, as shown. As will be observed, the vertical column of fluid pulp 18, is substantial 20 in height and serves to accentuate the force of the discharge at the bottom of the hopper.

While a portion of the fluid pulp flows vertically downward through the central opening 13 into the mercury 17, the major portion of such fluid is discharged through the spouts formed by the openings 14 and the lips 15, the positioning of such spouts being such as to cause the fluid to be injected tangentially into the mercury and there- 25 by causing a rotary movement to the mixture so long as the pulp continues to flow. By reason of the narrow passageway formed between the parallel telescoping walls of the funnel shaped bottom 8 and 12, the mercury where the ore pulp 30 enters such passageway is in the form of a thin uniform layer so that when such pulp has im- 35 parted to it a whirling motion through the tan- gential slots 14, every principle of such pulp is dashed into and against the layer of mercury with 40 considerable force and necessarily caused to come in intimate contact therewith to an extent hereto- 45 fore unknown in the art. The effect of such op- eration is to thoroughly associate the pulp with the mercury and to cause the gold, silver, or other metals therein to form an amalgam and to be held in the mercury and prevented from proceeding further, while the remainder 19 of the fluid from 50 which the metals have been extracted will flow upwardly and out through the spout 6. This op- 55 eration is ordinarily permitted to proceed until the mercury in the form of an amalgam has acquired as much gold, silver, or other metals as the mercury is capable of absorbing, at which time the flow of pulp is shut off and the faucet 7 is opened 60 and the bulk of the remaining pulp drawn off, when the mercury amalgam, and other fluid is released through the outlet 9 by turning valve 10, and is collected in some convenient receptacle. The amalgam is then removed and through the 65 manner of treatment well known in the art the valuable metals are then recovered. To resume treatment of further bodies of ore the mercury is again placed in the funnel 8, the pulp introduced into the hopper, and the process is repeated.

65 While I have described and illustrated my in- vention as embodied in the preferred form set forth, I by no means desire to limit myself to such form. As is obvious other forms might be employed without departing from the spirit and 70 purpose of my invention. The present embodiment is therefore to be considered, in all respects, as illustrative and not restrictive, the scope of the invention being indicated by the appended claims, rather than by the foregoing description, and all

changes which come within the meaning and range of equivalency of the claims are therefore intended to be embraced therein.

What I claim and desire to secure by Letters Patent is:

1. In an apparatus for concentrating ores, an elongated hopper for containing ore pulp, two telescoping recepable members arranged for holding a layer of mercury of substantial uniform thickness therebetween, and means for projecting 10 said pulp into said mercury tangentially and im- parting a rotary movement thereto.

2. In a receptacle for concentrating ores, a hopper having a funnel-shaped bottom for containing ore pulp, said hopper being provided with 15 a plurality of tangential outlets at the bottom thereof, a receptacle having a funnel-shaped bottom for mercury surrounding said outlets and in proximity thereto, in such position as to have im- parted by the flow of ore pulp through said out- 20 lets a rotary movement in the space between said bottoms.

3. In a receptacle for concentrating ores, an elongated hopper for ore pulp having a funnel- 25 shaped bottom, said bottom to be provided with outlets tangential thereto, an elongated receptacle enclosing said hopper and having a funnel-shaped bottom with its wall in proximity and substan- tially parallel to the wall of the bottom of said hopper, in such position as to have imparted 30 through the outflow of ore pulp through said outlets a vortex movement in the space between said walls.

4. In a receptacle for concentrating ores, an elongated hopper for ore pulp having a funnel- 35 shaped bottom, said bottom being provided with outlets tangential thereto, an elongated receptacle enclosing said hopper and having a funnel-shaped bottom with its wall in proximity and substan- tially parallel to the wall of the bottom of said 40 hopper, in such position as to have imparted through the outflow of ore pulp through said outlets a vortex movement in the space between said walls, and said hopper being built in space relation to said receptacle and being readily removable therefrom.

5. In a receptacle for concentrating ores, an elongated hopper for ore pulp having a funnel- 50 shaped bottom, said bottom being provided with outlets tangential thereto, an elongated tank en- 55 closing said hopper and having a funnel-shaped bottom with its wall in proximity and substan- tially parallel to the wall of the bottom of said hopper in such position as to have imparted through the outflow of ore pulp through said outlets a rotary movement in the space between said walls, said tank being provided with an over-flow outlet near the top thereof at a substantial dis- 60 tance above the bottom thereof.

6. In an apparatus for concentrating ores, a 60 hopper for containing ore pulp having a funnel- shaped bottom provided with tangential outlets, a receptacle for mercury having a funnel-shaped bottom the wall of which is substantially parallel to the wall of the bottom of said hopper and is 65 located so as to provide a passageway between said walls communicating with said outlets, whereby said ore pulp may be permitted to flow by gravity through said outlets into said passageway and to mix with said mercury and to impart a 70 rotary movement thereto.

FRANKLIN F. GRANT.
